UNITED STATES PATENT OFFICE

2,059,241

LASTING MACHINE

Jacob C. Jorgensen, Beverly, Mass., assignor to
United Shoe Machinery Corporation, Paterson,
N. J., a corporation of New Jersey

Application April 19, 1935, Serial No. 17,290

56 Claims. (Cl. 12—4)

This invention relates to lasting machines, and is herein illustrated as embodied in a heel-end-lasting machine of the same general type as disclosed in United States Letters Patent No. 1,583,044, granted on May 4, 1926 upon an application of C. H. Hoyt, but provided with wiping and tacking mechanism constructed in many respects substantially as disclosed in Letters Patent No. 1,852,015, granted on April 5, 1932 upon an application of mine. It is to be understood, however, that in various novel aspects the invention is not limited to machines of the illustrated type or to machines for lasting the heel ends of shoes.

In machine organizations of the character disclosed in the above-mentioned Letters Patent the heel-lasting wipers are operated by a path cam through force directed lengthwise of a shaft which carries the cam. One object of the present invention is to minimize end thrust of the cam shaft in the wiper operation; and for this purpose, in the construction herein shown, the advancing movement of the wipers lengthwise of the shoe and their closing movements laterally of the shoe are effected respectively by different members which are movable respectively in opposite directions and are operated by different cams on the cam shaft, so that the force tending to move the shaft in one direction in effecting the advancing movement of the wipers is substantially balanced by the force tending to move it in the opposite direction in effecting the closing of the wipers. This minimizes wear and also reduces the amount of power required to operate the machine. Novel features are also to be recognized in mechanism provided for closing the wipers by the movement of one of the above-mentioned members, including means whereby the wipers may be preliminarily adjusted toward or from each other for shoes of different widths.

As in prior machines of the illustrated type, the machine herein shown includes a heel band for clamping the upper materials about the heel end of the last, and the invention further provides novel means for controlling the heel band. In accordance with one feature provision is afforded for quickly adjusting both the forward ends of the heel band simultaneously in the same direction to the right or the left relatively to the rear end of the band, so that the band will properly position right or left shoes relatively to the same wipers as more particularly hereinafter explained. As illustrated, the heel band is closed and opened laterally of the shoe through a pair of bell-crank levers operated by rack bars which are movable

both in the same direction to close or to open the band, and the forward ends of the band are adjusted as above described by movements of these rack bars respectively in opposite directions through a member connected to both of them. Novel means is further provided for adjusting the forward ends of the heel band toward or from each other for shoes of different widths, this adjustment in the construction shown being effected by relative movements of two connected members which are movable together in the same direction lengthwise of the shoe to close or open the band. Improved means is also provided for controlling the heel band in locations opposite the corners of the heel end of the shoe to insure adequate pressure of the band on the shoe in these locations.

As common heretofore in machines of the illustrated type, the machine herein shown is provided with a plurality of drivers for driving fastenings, preferably tacks, to fasten the upper in lasted position; and in accordance with a further feature of the invention the driver-operating means is so constructed as to operate with less force if the machine is run idly, i. e., with no shoe on the shoe support, than when it is operating on a shoe. This serves to lessen the force of impact of stop mechanism which limits the movement of the driver-operating means, and accordingly minimizes noise and wear and tear when the machine is run idly, as it may be, for example, for test purposes. In the construction shown the drivers are operated, as heretofore, by a spring-impelled member, and for the purpose in view there is provided spring means which operates this member with comparatively little force if there is no shoe in the machine and additional spring means, controlled by a shoe on the shoe support, for increasing the force with which the member is operated in the presence of such a shoe.

The invention further provides means whereby the machine may be readily adapted to drive the fastenings only part way into a shoe in case, for example, it may be desired to secure the upper materials permanently in lasted position by adhesive and to use the fastenings only for holding the upper temporarily until the adhesive has hardened. For this purpose provision is afforded for quickly adjusting the above-mentioned stop mechanism to prevent the drivers from driving the fastenings all the way into the shoe. In the construction shown, as heretofore, the fastenings are driven through openings in the wipers, and in order to permit the retractive movement

of the wipers without interfering with such partially driven fastenings, there is provided means for moving the shoe heightwise far enough to withdraw the fastenings from the openings in the wipers before the latter are retracted. When the fastenings are thus only partially driven, it is desirable that the driver-operating means shall operate with less force than when they are fully driven, and accordingly the construction shown 5 is further such that in partially driving the fastenings this means operates only with the same force with which it would operate if there were no shoe in the machine. For this purpose, provision is afforded for maintaining inoperative, even 10 though there is a shoe in the machine, the additional spring means above referred to as controlled by the shoe for operating the spring-im- 15 pelled member.

The above and other features of the invention, 20 including also novel means adapting the machine to operate on long-legged boots, novel means for relieving the clamping pressure on the shoe in case the machine fails to complete its cycle because of abnormal resistance of the shoe 25 to the movement of the wipers, and various novel details of construction and combinations of parts, will now be more particularly described by reference to the accompanying drawings and pointed out in the claims.

30 In the drawings,

Fig. 1 is a view in front elevation of a machine in which the invention is embodied;

Fig. 2 is a view of the machine in left-hand side elevation, with parts broken away;

35 Fig. 3 is mainly a plan view of a portion of the structure, including the wipers and their operating mechanism;

Fig. 4 is a section mainly on the line IV—IV of Fig. 2, on an enlarged scale;

40 Fig. 5 is a section on the line V—V of Fig. 4; Fig. 6 is a section on the line VI—VI of Fig. 4; Fig. 7 is a section on the line VII—VII of Fig. 1, on an enlarged scale;

Fig. 8 is a section on the line VIII—VIII of Fig. 7, on an enlarged scale, showing the heel band and its operating mechanism;

45 Fig. 9 is a section on the line IX—IX of Fig. 8; Fig. 10 is a section on the line X—X of Fig. 7; Fig. 11 is a section on the line XI—XI of Fig. 50 10;

Fig. 12 is a section on the line XII—XII of Fig. 7;

Fig. 13 is a section on the line XIII—XIII of Fig. 12, on an enlarged scale;

Fig. 14 is a section on the line XIV—XIV of Fig. 2, on an enlarged scale;

Fig. 15 is a section on the line XV—XV of Fig. 2, on an enlarged scale;

60 Fig. 16 is a section on the line XVI—XVI of Fig. 15;

Fig. 17 is a view in side elevation, on an enlarged scale, of a portion of the structure shown in Fig. 2, with parts broken away;

65 Fig. 18 is a section on the line XVIII—XVIII of Fig. 3;

Fig. 19 is a view partly in left-hand side elevation and partly in vertical section, showing the lower portion of the shoe support or jack and the 70 mechanism for controlling the jack post;

Fig. 20 is a section on the line XX—XX of Fig. 19;

Fig. 21 is a view in front elevation of a portion 75 of the structure shown in Fig. 19;

Fig. 22 is a developed plan view of some of the operating cams;

Fig. 23 is a perspective view of a portion of the starting and stopping mechanism;

Fig. 24 is a vertical section showing certain 5 details of the wiping and tacking mechanism and illustrating the relation of this mechanism to the shoe prior to the inward movements of the wipers;

Fig. 25 is a vertical section illustrating the relation of the wiping and tacking mechanism to the 10 shoe at the end of the inward movements of the wipers and showing more of the structure than is shown in Fig. 24;

Fig. 26 is a section on the line XXVI—XXVI 15 of Fig. 25;

Fig. 27 is a view similar to Fig. 24, but illustrating the positions of the parts when the tack drivers are at the end of their driving movements;

Fig. 28 is a plan view of a portion of the wiping 20 and tacking mechanism with the parts in the same positions as in Fig. 25;

Fig. 29 shows in side elevation an alternative 25 shoe support or jack so constructed as to adapt it to receive long-legged boots;

Fig. 30 is a plan view of a portion of the structure shown in Fig. 29;

Fig. 31 is a view similar to a portion of Fig. 25, but illustrating the positions of the parts when the tacks are driven only part way into the shoe; 30

Fig. 32 shows in side elevation a portion of the 35 tacking mechanism with the parts in the positions which they occupy at the end of the tack-driving operation when the tacks are driven as shown in Fig. 31.

The machine in which the invention is herein 40 shown as embodied is, as above stated, a machine of the same general type as that disclosed in Letters Patent No. 1,583,044, but having wiping and tacking mechanism constructed in many respects substantially as disclosed in Letters Patent No. 1,852,015. The machine includes in its organization a heel band 2 for embracing and clamping 45 the upper about the heel end of the last, wipers 4 for wiping the marginal portion of the heel end of the upper inwardly over the insole or other shoe bottom part, which may be referred to generically as the sole, means hereinafter described 50 for driving tacks through openings in the wipers to fasten the upper, and a holdown 6 for engaging the heel end of the sole to determine the position of the shoe and last heightwise in the lasting operation. The shoe and last are 55 mounted on a shoe support or jack which is movable to carry them lengthwise into position to be embraced by the heel band 2 and which has also means for carrying the shoe upwardly against the holdown 6.

60 The jack (Figs. 1 and 2) includes a heel pin or spindle 8 arranged to enter the usual spindle hole in the heel end of the last and mounted fast in a block 10 which is movable with the last and shoe about an axis extending lengthwise of the shoe and located approximately at the heel-seat to permit each shoe to be so positioned that its heel seat extends laterally in substantially parallel relation to the plane of the wipers, as disclosed in Letters Patent No. 1,896,121, granted on February 7, 1933 upon an application of mine. As further disclosed in greater detail in Letters Patent No. 2,001,732, granted on May 21, 1935 upon another application of mine, the top face of the cone of the last rests upon a member 12 which 75

adjusts itself to that face of the last by movement relatively to the spindle 8 and the block 10 about an axis extending widthwise of the last. The block 10 is mounted on a post 14, and 5 clamped to this post is a forwardly extending bar 16 which carries means for supporting the fore-part of the shoe and last. This means differs in no substantial respect from means provided heretofore for the same purpose in machines of 10 the illustrated type. It comprises a toe rest 18 mounted on a casting 20 which is adjustable in directions heightwise of the shoe by a pinion 21 in the casting engaging teeth on an upwardly extending bar 22 on which the casting slides, the 15 pinion being turned by a hand wheel 24 (Fig. 1). A ratchet wheel 26 which turns with the pinion 21 is engaged by a pawl 28 to hold the casting 20 and the toe rest thereon against downward movement from any adjusted position, the pawl being 20 movable upwardly to release the ratchet wheel and permit lowering of the toe rest. The bar 22 extends upwardly from a holder 30 adjustably movable along the bar 16 for shoes of different 25 lengths and held in adjusted position by a pair of pawls 32 (Fig. 2) the tails of which may be pressed toward each other to release the holder and permit its adjustment along the bar, the 30 pawls engaging teeth on the bar.

The post 14 on which the above-described 35 parts of the jack are supported is slidably mounted in a holder 34 which is supported on two pins 36 (Fig. 19) for swinging movements in directions laterally of the shoe, substantially as disclosed in Letters Patent No. 2,001,732, to permit the heel end of each shoe to be readily centralized relatively to the heel band regardless of the locations of the spindle holes in different lasts. Means differing somewhat in details from the construction shown in the last-mentioned 40 Letters Patent is provided for limiting symmetrically opposite swinging movements of the holder 34 and for fixing the holder in a centralized position if desired. This means comprises a slide 38 (Figs. 19 and 21) movable downwardly and 45 upwardly in a recess provided in a depending portion of the holder 34 and confined in the recess by a plate 40 fastened to the holder. The slide 38 at its lower end has therein a recess 42 with diverging side walls arranged to be engaged 50 by a lug 44 on a member 45 to limit the opposite swinging movements of the holder 34, the member 45 being secured to a casting 46 in which the above-mentioned pins 36 are mounted. In Figs. 55 19 and 21 the slide 38 is shown in its uppermost position, in which position it permits limited swinging movements of the holder 34 for the purpose described. By means of a knob 48 connected to the slide 38 through a slot 50 in the plate 40 the slide may be moved downward far 60 enough to cooperate with the lug 44 to lock the holder 34 in a centralized position. The slide 38 is held either in its uppermost position or in its locking position by a pin 52 mounted in the holder 34 and pressed inwardly by a leaf spring 54 so 65 as to enter one or the other of two conical recesses 56 in the slide. When the slide 38 is in its uppermost position the holder 34 is nevertheless held normally in a centralized position by a spring 58 which is mounted partly in a recess in 70 the member 45 and acts at its opposite ends on two depending lugs at the lower end of the holder 34, as will be evident by reference to Figs. 19 and 21.

The post 14 is supported at its lower end on a 75 member 60 (Fig. 19) slidably mounted in the

holder 34, the lower end of the post having thereon depending fingers arranged to enter stepped recesses in the member 60 to support the post at different heights for lasts that vary considerably in height, in substantially the same 5 manner as illustrated in Fig. 19a of the above-mentioned Letters Patent No. 1,583,044. A finer adjustment of the height of the post may be effected by upward or downward adjustment of the member 60 through a screw 66 which is threaded 10 therein, the head of this screw being supported on a cap 68 which is mounted for universal rocking movements on a stem 70 at the upper end of a rod 72. The rod 72 is movable upwardly and downwardly in a bearing in the casting 46 and is 15 provided with a flange 74 which by contact with the casting limits its downward movement. The upward movement of the rod 72 serves to lift the shoe by moving the member 60 and the post 14 upwardly, the rod being connected for this 20 purpose to a slide 76 movable upwardly and downwardly in the lower end portion of the casting 46. When the shoe is first mounted on the spindle 8, however, the jack is in a forwardly inclined position, as illustrated in Figs. 2 and 19, 25 and the jack must be swung rearwardly to carry the heel end of the shoe to a position under the holdown 6 before the shoe is raised by the slide 76. For the purpose of such swinging movement the jack casting 46 is supported rotatably on two 30 pins 78 (Figs. 1 and 2) mounted in a bracket 80 fast on the frame. For determining the initial forwardly inclined position of the jack there is pivotally connected to a pair of upwardly and rearwardly extending arms 82 of the casting 46 35 a bar 84 (Figs. 2, 4, 6 and 7) which is mounted in a slideway formed in a holder 86. The holder 86 is sleeved on a shaft 88 mounted in bearings in the frame for a purpose hereinafter described, so that the holder may turn as required by the 40 slight raising and lowering of the forward end of the bar 84 in the swinging movements of the jack. To limit the forward swinging movement of the jack the bar 84 carries a pin 90 (Fig. 7) 45 arranged to engage a shoulder on the holder 86. The weight of the jack is partially balanced by a counterweight 92 (Fig. 2) supported on a cable 94 which extends over a pulley 96 and is connected at its forward end to the arms 82 of the jack. This facilitates the rearward swinging 50 movement of the jack, but does not prevent the latter from swinging forwardly to its idle position by its own weight.

The rearward swinging movement of the jack to carry the heel end of the shoe to a position 55 within the heel band 2 and beneath the holdown 6, and the upward movement of the post 14 to force the shoe against the holdown, are effected by the operator prior to the starting of the power operation of the machine. For this purpose 60 there is provided a treadle 98 (Fig. 2) which is pivoted at 100 on a bracket on the frame and is movable against the resistance of a spring 102 which bears downwardly on its rear end, the spring being engaged at its upper end by a member 104 threaded in the frame and adjustable to 65 vary the stress of the spring. The treadle 98 is connected by a link 106 (Figs. 2 and 19) to one arm of a lever 108 which is fulcrumed on a rod 110 mounted on a bracket 112 on the lower end 70 of the jack casting 46. The other arm of the lever 108 bears against the lower end of the slide 76. It will thus be evident that by the depression of the treadle 98 the slide 76 and the parts controlled thereby may be raised to force the shoe 75.

against the holdown 6, and it will be further evident that by reason of the relation of the link 106 to the fulcrum 110 of the lever 108 the depression of the treadle also serves to swing the 5 jack rearwardly about the pins 78. Since, however, the shoe should not be raised until after it has been carried to a position under the holdown, the operator will hold the post 14 from rising by pressure of his hands on the shoe until 10 after the jack has substantially completed its rearward movement. Near the end of the rearward movement of the jack a pin 113 (Fig. 7) on the bar 84 engages and forces rearwardly a spring-controlled plunger 114 which is mounted 15 in a member 115 fast on the holder 86. This plunger serves later to initiate the return movement of the jack which is completed by gravity.

After the starting of the power operation of the machine the jack and its post 14 are controlled automatically. For such control of the post 14 there is provided a lever 116 (Fig. 19) which is fulcrumed on a rod 117 on the bracket 80 and is provided at its forward end with a roll 118 lying in a transverse slot in the slide 25 76. At its rear end the lever 116 is enlarged and forked to provide arms on the ends of which are secured a curved rack bar 120. This rack bar is engaged by a pinion 122 which is mounted to turn on a fixed rod 124, and integral with the 30 pinion is a ratchet wheel 126 (Figs. 19 and 20). This ratchet wheel is engaged and turned in a counterclockwise direction (Fig. 19) by one or the other of two pawls 128 supported on a pawl carrier 130 which is mounted to turn about the 35 rod 124. The pawls 128 are preferably mounted and controlled in the same manner as disclosed in Letters Patent No. 2,046,462, granted on July 7, 1936 upon an application of mine, which may be referred to for a more complete understanding 40 of details not herein disclosed. It will be understood that when the pawl carrier 130 is turned in a counterclockwise direction (Fig. 19) about the rod 124 the ratchet wheel 126 and the pinion 122 are turned to force the jack post 14 upwardly. 45 This serves to force the shoe more firmly against the holdown 6, and later to raise the shoe farther concurrently with an upward movement of the holdown, as more particularly hereinafter explained. To vary the amount of force thus 50 imparted to the post 14 there is provided, as further disclosed in the last-mentioned Letters Patent, a control disk 132 which releases the pawls and permits them to engage the ratchet wheel after a variably determined amount of initial 55 movement of the pawl carrier 130, the disk 132 being adjustable by a hand wheel 134 connected to a sleeve 136 on which the disk is formed. The pawl carrier 130 is operated by a lever arm 138 (Figs. 2, 4 and 17) which is integral with a sleeve member 139 mounted to turn on a rod 140 on the frame and is connected to the pawl carrier by a yieldable link comprising a rod 142, a spring 144 (Fig. 19), and another rod 146. The rod 142 is pivotally connected at its upper end to the 60 lever arm 138 and is provided at its lower end with a disk 148 in engagement with the lower end of the spring 144. Slidably mounted on the rod 142 is a casing 150 which serves as a housing for the spring 144 and is connected to the pawl carrier 130 by the rod 146. It will be understood 65 that operative movement is imparted to the pawl carrier by upward movement of the lever arm 138 and that the spring 144 may yield more or less in response to resistance of the holdown 70 to upward movement of the shoe. The recess 75

in the rear end of the lever 116 in which the pinion 122 is located is inclosed on opposite sides by two shield plates 152 which are fastened to the bracket 80 and between which the lever is movable.

The automatic control of the jack with respect to swinging movement about the pins 78 is effected through the bar 84 (Figs. 6 and 7). For this purpose the bar is provided with rack teeth 154 engaged by a pinion 156 which is keyed to the shaft 88, and integral with this pinion is a ratchet wheel 158 (see also Fig. 17) which is engaged and operated by one or the other of two spring-pressed pawls 160 pivotally mounted on a pawl carrier 162. This pawl carrier is rotatably mounted partly on the hub of the ratchet wheel 158 and partly on a sleeve 164 on the shaft 88, this sleeve having formed on its inner end a disk 166 which releases the pawls and permits them to engage the ratchet wheel after a variably determined amount of initial movement of the pawl carrier. The disk 166 is adjustable by a hand wheel 168 connected to the sleeve 164, so as to vary the amount of movement imparted to the ratchet wheel 158 and the pinion 156 by the pawls 160. Operative movement is imparted to the pawl carrier 162 through a link 170 (Fig. 17) by a lever arm 172 which is integral with the previously mentioned sleeve member 139 and therefore swings with the lever arm 138 about the rod 140. It will thus be seen that movement is imparted to the jack by the lever arm 172 to force the shoe more firmly backward against the heel band simultaneously with the movement of the lever arm 138 to force the jack post 14 upwardly.

Movement of the two lever arms 138 and 172 in a counterclockwise direction (Fig. 17) for the purposes above described is effected by a path cam 174 (Figs. 2, 7, and 22) formed in a cam 40 drum 176 which is fast on a forwardly and rearwardly extending cam shaft 178 mounted in bearings in the frame of the machine. The cam 174 engages a roll 180 carried by a slide 182 (Figs. 2 and 18) which is horizontally movable in guideways on the frame. The slide 182 is provided with rack teeth 184 in engagement with teeth formed on one arm of a lever 186 which is pivoted on a pin 188 on the frame, and the other arm of this lever is connected by a link 190 to an arm 192 projecting from a member 194 rotatably mounted on the rod 140 at one end of the sleeve member 139. Mounted in another arm 196 of the member 194 is a pin 198 (Fig. 17) arranged to engage the upper face of a lug 200 formed on a block 202 (see also Fig. 4) which is secured to the sleeve member 139. It will thus be seen that as the member 194 is turned in a counterclockwise direction (Fig. 17) it serves through the pin 198 to swing in the same direction the two connected lever arms 138 and 172. Since the lever 186 is operated positively by the cam 174 and acts positively, through the connections described, on the bar 84 connected to the jack, the swinging movement imparted to the jack by the cam 174 is a positive movement. As herein-after more particularly described, such positive rearward movement of the jack, accompanied by upward movement of the jack post 14, occurs shortly after the starting of the power operation 60 of the machine simultaneously with the closing of the heel band 2 against the side of the shoe before the wipers 4 begin to operate on the shoe. As shown in Fig. 22, moreover, the cam 174 is so shaped that at a later stage in the cycle of the 65 70 75 80 85 90 95 100 105 110 115 120 125 130 135 140 145 150 155 160 165 170 175 180 185 190 195 machine, immediately prior to a second inward wiping movement of the wipers over the heel seat, the jack is operated to force the shoe still more firmly back against the heel band and the jack post 14 is further raised, coincidently with an upward movement of the holdown 6, to position the bottom of the heel end of the shoe slightly higher in the second overwiping movement of the wipers than in their first overwiping movement.

Before the jack receives its first positive rearward movement in the power operation of the machine as above described, it is operated upon by additional means to press the shoe yieldingly back against the heel band while the heel band is still in an open position. For this purpose there is keyed to the shaft 88 (Figs. 5 and 6) a ratchet wheel 204 which is operated by one or the other of two spring-pressed pawls 206 mounted on a pawl carrier 208. The pawl carrier 208 is mounted in part on the hub of the ratchet wheel 204 and in part on a sleeve 210 on the shaft 88 for turning movement about the axis of the shaft. Formed on the inner end of the sleeve 210 is a control disk 212 which releases the pawls 206 to permit them to act on the ratchet wheel at a variably predetermined time after the starting of the movement of the pawl carrier 208, the disk being adjustable to vary such time of engagement of the pawls with the ratchet wheel by means of a hand wheel 214 connected to the sleeve 210. The pawl carrier 208 is operated through a link 216 by a lever 218 (Fig. 18) which is mounted to turn on a pin 220 on the frame. The link 216 extends through a pin 222 which is swiveled in the lower arm of the lever 218 and is engaged on one side by a flange 224 on the link and on the other side of a member 226 slidably mounted on the link. Between the member 226 and another member 228 which is held on the link by nuts 230 is a compression spring 232. It will thus be seen that when the lever 218 is swung in a clockwise direction (Fig. 5) it acts yieldingly through the spring 232 on the link 216 to turn the pawl carrier 208 and through the pawls 206 to turn the shaft 88 on which the pinion 156 engaging the bar 84 is secured as hereinbefore described. It will be evident that in such turning movement of the shaft 88 the ratchet wheel 158 turns relatively to the pawls 160 through which the shaft is later operated to impart the positive movement to the jack as previously described. For operating the lever 218 there is provided a slide 234 (Figs. 5 and 18) having rack teeth 236 in engagement with teeth on the upper arm of the lever, this slide carrying a roll 238 engaged by a path cam 240 (Figs. 2, 7 and 22) in the cam drum 176. The heel band 2 may be formed, for example, as customary heretofore, of leather molded in approximate conformity to the contour of the heel end of a shoe but sufficiently flexible to conform to small variations in the contours of shoes of different styles and sizes. At its rear end the band is secured to an angular clip 242 (Fig. 7) supported by a screw 243 on the lower end of a cylindrical stem 244 extending downwardly from a member 246 which is supported on a slide 248, the member 246 being arranged to serve as an abutment for engagement with the upper portion of the rear face of the heel band. Near its front ends the heel band is supported on angular clips 250, one of which is shown most clearly in Fig. 25, these clips providing guideways along which the opposite side portions of the band

may slide in directions lengthwise of the shoe. Each of the clips 250 is secured to the lower end of a cylindrical stem 252 extending downwardly from a block 254 arranged to bear against the upper portion of the side of the band, the stem 252 being mounted for rotation and also for limited upward movement in a slide 256 supported on an arm 258 (Fig. 8). Each arm 258 is mounted to swing in directions widthwise of the shoe about a rod 260 on the frame and is operated by means hereinafter described to effect the closing and opening of the heel band. Each slide 256 is adjustable in directions lengthwise of the shoe on the arm 258 on which it is mounted, and is secured in adjusted position by a bolt 262 which extends through a slot in the slide.

Mounted to swing about a stud 264 which is threaded in the member 246 are two curved arms 266 on which are pivotally mounted blocks 268 arranged to engage the outer face of the heel band in locations substantially opposite the corners of the heel end of the shoe. Each arm 266 is engaged on its outer face, in a location substantially opposite the block 268, by a plunger 270 supported on an arm 272 extending laterally from the member 246. The plunger 270 is slidably mounted in a bushing 274 which is threaded in the arm 272, and is provided with a flange 276 arranged to engage a shoulder on this bushing to limit movement of the plunger in a direction toward the heel band. The plunger 270 has a stem 278 slidably movable in an opening formed in a nipple 280 which is threaded in the bushing 274, and between this nipple and the plunger are mounted two springs 282 and 284, the two springs performing the function of a single spring. The force with which the springs act may be varied by adjustment of the nipple 280. Light springs 286 abutting against the arms 266 and portions of the member 246 hold these arms at all times in contact with the plungers 270. The bushings 274 may be turned by a wrench to adjust them inwardly or outwardly in the arms 272 and thus to vary the initial positions of the plungers 270 without altering the stresses of the springs 282 and 284. As the parts are initially positioned, the heel band is preferably held by the plungers 270 with its rear-end portion spaced somewhat forwardly of the rear abutment 246, as shown in Figs. 7 and 8, this being permitted by a slot in the clip 242 through which the screw 243 extends. Accordingly when the shoe is forced yieldingly back against the heel band by the mechanism shown in Fig. 5 prior to the closing of the band, the plungers 270 yield against the resistance of their controlling springs 282 and 284 until the band in its rearward movement with the shoe seats against the abutment 246, the forward end portions of the band sliding upon the supporting clips 250. Insurance is thus afforded that adequate pressure will be applied through the band at the corners of the heel end of the shoe. A short upward movement of the band with the shoe when the shoe is raised between the first and second inward movements of the wipers is permitted by clearance between the clips 250 and the lower faces of the slides 256 (Fig. 25) and between the clip 242 and the lower face of the slide 248 (Fig. 7). It will be understood that the member 246 and the parts supported thereon are raised with the band.

The slide 248 on which the heel band is supported at its rear end and on which also are supported the member 246 and the parts thereon, is

adjustable in directions lengthwise of the shoe in a bracket 288. In this manner the heel band is adjusted bodily to vary the position of the heel-end face of the shoe when pressed firmly against the band, so as to determine as desired the distance that the wipers will advance over the rear end of the heel seat and therefore the distance from the rear edge of the heel seat at which the rearmost tacks will be driven. For the purpose of such adjustment the slide 248 (Figs. 7 and 9) is provided on its lower face with rack teeth engaged by a pinion 290 formed integral with a shaft 292 mounted in bearings in the bracket 288 and in the frame, this shaft being rotatable by means of a crank arm 294 fast on its outer end. Slidably mounted in the arm 294 is a detent 295 arranged to engage teeth formed on a stationary block 298 to hold the shaft 292 in adjusted position. When it is desired to adjust the shaft the detent is pulled out of engagement with the teeth by means of a knob 300 fast on a stem 302 which extends outwardly from the detent through an opening in the arm 294. The detent is held normally in locking position by a spring 304. It will be understood that when the heel band is adjusted bodily as described its forward end portions slide along the supporting clips 250.

For closing and opening the heel band the previously mentioned arms 258 are operated by bell-crank levers 306 mounted to swing about rods 308 and connected to the arms 258 by links 310. Formed on one arm of each bell-crank lever 306 is a gear sector 312 in engagement with teeth of a rack bar 314 mounted in guideways formed in part in the bracket 288 and in part in a slide 316 which is movable in directions lengthwise of the shoe in guideways in the frame. The two rack bars 314 are connected together by a short lever 318 which has teeth on its opposite ends in engagement with teeth on the rack bars, this lever, as shown in Fig. 7, being keyed to a vertical shaft 320 mounted in bearings in the slide 316. This shaft is held normally against turning movement by means hereinafter described, so that in the operation of the machine the two rack bars 314 are prevented from moving relatively to each other. The lever 318 accordingly serves as a connection between the slide 316 and the two rack bars whereby the latter are operated in unison by movement of the slide to swing the bell-crank levers 306 in directions to close the heel band against the sides of the shoe. Such movement of the slide 316 is effected yieldingly through a spring 322 (Figs. 7 and 8) by another slide 324 mounted on guideways in a recess in the slide 316 (see Fig. 18), the slide 324 being provided with rack teeth engaged by teeth of a gear sector 326 formed integral with the previously mentioned sleeve member 139 which carries the two levers 138 and 172 (Fig. 4). It will be understood that the closing of the heel band results from rearward movement of the slide 324 in response to the turning of the member 139 in a counterclockwise direction (Fig. 17) for also operating the jack and the jack post as hereinbefore described. The spring 322 bears at its forward end against a shoulder on the slide 324, and at its rear end it is seated in a bushing 328 which is threaded in an opening in the slide 316. Extending through the spring 322 is a rod 330 having on its forward end a head for engaging the front face of the slide 324 and having threaded on its rear end a nut 332 arranged to abut against the rear end of the threaded bushing 328. When

the slide 324 receives its forward return movement it returns the slide 316 positively to starting position by contact therewith, as illustrated in Fig. 7, thus opening the heel band.

Adjustment of the forward ends of the heel band toward or from each other for shoes of different widths is effected by movement of the slide 316 relatively to the slide 324 while the latter is held fixed in its initial position by its connection with the gear sector 326. For this purpose the threaded bushing 328 (Figs. 7 and 8) has integral therewith a pinion 334 which is engaged by another pinion 336 mounted on a stud 338 supported on a depending portion of the slide 316. The pinion 336 is engaged and operated by a pinion 340 (Figs. 8 and 18) which is fast on a shaft 342 mounted in bearings in the slide 316 and in the frame, this shaft having on its forward end a knurled wheel 344 for turning it. As will be evident by reference to Fig. 1, the wheel 344 is readily accessible to the operator when there is no shoe in the machine. As the bushing 328 is turned by this adjusting mechanism it is held from moving bodily in one direction by the spring 322 and in the other direction by the nut 332 on the rod 330, and accordingly the result of its turning movement is to move the slide 316 relatively to the slide 324, thereby moving the ends of the heel band simultaneously toward or from each other through the rack bars 314 and the bell-crank levers 306. The pinion 336 is sufficiently elongated to maintain contact with the pinion 334 in such adjusting movement of the slide 316, and a flange 346 on the pinion 336 will serve by contact with the pinion 334 to prevent excessive adjusting movement of the slide in one direction, excessive movement in the other direction being prevented by contact of the slide 316 with the pinion 334.

For holding the short lever 318 against turning movement about the shaft 320 during the operation of the machine as above described, there is fast on the lower end of the shaft an arm 348 (Figs. 1 and 7) which carries a detent 350 arranged to engage teeth 352 formed on the slide 316. By means of the arm 348 the shaft 320 and the lever 318 thereon may be turned in one direction or the other to effect simultaneous movements of the rack bars 314 in opposite directions and thereby to move the forward ends of the heel band simultaneously to the right or the left at the will of the operator. In this manner the heel band may be preliminarily adjusted to insure that it will position the heel ends of right or left shoes in proper relation to the wipers, which are not changed for rights and lefts, so that the wipers will move inwardly the proper distances at both sides of the heel seat and that the tacks will be driven at the proper distances from the side edges of the heel seat. That is, in operating, for example, on a right shoe of a style having a comparatively narrow shank portion with a pronounced lateral curvature at the inner side of the shoe from the heel end inwardly toward the shank portion, the forward ends of the heel band will be adjusted to the left so that the tacks will be located far enough inwardly from the edge of the heel seat at the inner side of the shoe. To permit such adjustment the detent 350 is movable out of engagement with the teeth 352 by the turning of a knurled member 354 which has a sleeve portion 356 threaded in the arm 348 and which engages a collar 358 fast on the end of a rod projecting from the detent. It will thus be understood that when

the member 354 is turned in one direction it acts on the collar 358 to force the detent away from the teeth 352. When it is turned in the other direction its sleeve portion acts by engagement 5 with a shoulder 360 on the above-mentioned rod to force the detent again into locking position. The knurled member 354 and the arm 348 are readily accessible to the operator from the front of the machine when there is no shoe in the 10 chine.

From the foregoing description it will be evident that the heel band is forced against the sides of the shoe, the jack is operated positively to force the shoe more firmly back against the 15 heel band, and upwardly directed force is applied to the jack post 14, all by the turning movement of the sleeve member 139 about the rod 140 through the operation of the cam 174. As hereinbefore described, moreover, the operative 20 turning movement is imparted to the sleeve member 139 through the pin 198 (Figs. 4 and 17) which is mounted in the operating member 194 and projects over the top of the lug 200 on the block 202 fast on the member 139 to operate 25 this member by contact with the lug. In a machine of the illustrated type it may happen, especially at the time of the second overwiping movement of the wipers, that resistance of the shoe to the movement of the wipers will cause 30 the machine to come to a stop without completing its cycle in case, for example, of improper adjustment of the hold-down 6. The construction herein shown is such that under those conditions the sleeve member 139 may be released 35 from its operating member 194, thus releasing the shoe from the pressure of the heel band and from the upwardly directed force of the jack post 14 sufficiently to permit the machine to complete its cycle of movements. For this purpose 40 the pin 198 (Fig. 17) is mounted to turn in the arm 196 of the member 194 and is recessed on one side to provide a flat face 362 which will clear the end of the lug 200 on the block 202 when the pin is in one position. Normally 45 the pin is in the position illustrated in Fig. 17, so that by engagement with the lug 200 it transmits operative movement from the member 194 to the sleeve member 139. To hold the pin in this position there is fast on the outer end there- 50 of an arm 364 held in engagement with a pin 366 on the member 194 by a torsion spring 368. The arm 364 may be turned in a clockwise direction (Fig. 17) into position to cause the pin 198 to clear the end of the lug 200 by a block 55 370 fast on the rear end of a rod 372 which is slidingly movable in bearings in the frame (Fig. 4). The rod 372 is held normally in its idle position by a spring 374 in engagement at one end with the frame and at its other end with a 60 collar 376 fast on the rod. For moving the rod 372 rearwardly to cause the block 370 to operate on the arm 364 there is provided a hand lever 378 (Figs. 1, 2 and 4) which is fast on a shaft 380 mounted in bearings in the frame. Also fast 65 on this shaft is a forked arm 382 provided with two pins 384 which extend into vertical slots 386 formed in a block 388 fast on the rod 372. It will be understood that when the pin 198 is turned into position to clear the end of the lug 200 the sleeve 70 member 139 turns in a clockwise direction (Fig. 17), due to expansion of the springs 144 (Fig. 19) and 322 (Fig. 7) and the weight of some of the parts, thereby relieving the pressure with which the shoe is held by the jack and the jack post 75 against the heel band and the hold-down and

with which it is clamped at its sides by the heel band. Such reverse turning movement of the sleeve member is permitted by clearance between a shoulder 390 thereon and a shoulder 392 on the member 194. The movement is limited by 5 engagement of a member 394 (Fig. 19), adjustably threaded on the rod 142, with washers 396 which rest on a disk 398 provided with a curved lower face seated upon a complementally curved upper face of a plate 400, this plate resting on 10 a portion of the frame adjacent to a slot 402 in the frame through which the rod 142 extends. In the return of the parts of the machine to starting positions as the machine completes its cycle of movements, the pin 198 is carried by 15 the member 194 to a position above the lug 200, whereupon the pin is turned by the spring 368 into position to act normally on the upper face of the lug in the next cycle of the machine.

Each of the two wipers 4 is secured to a tacker 20 block 404 (Figs. 1, 3 and 25) from which tacks are driven through openings in the wiper to fasten the upper in lasted position, one of these openings being shown at 406 in Figs. 24 and 25. Each wiper has thereon an upstanding flange 25 408 which cooperates with a plurality of spring-pressed tack fingers 410 (Fig. 26) mounted in recesses in the tacker block 404 to provide pockets to receive the tacks, substantially as disclosed in the previously mentioned Letters Patent 30 No. 1,852,015. Each tacker block 404 has tongue-and-groove connections 412 and 414 (Fig. 25) with a wiper carrier 416 which supports it. As illustrated in Fig. 3, these tongue-and-groove connections are curved so that the tacker block 35 and the wiper attached thereto may be conveniently disconnected from the wiper carrier by sliding the block forwardly if it is desired, for example, to substitute different wipers for operating on shoes of widely different sizes. Each 40 tacker block is secured to the wiper carrier 416 on which it is mounted by means of a screw 418 which may be conveniently removed from above when the wipers are in their closed positions, as 45 illustrated in Fig. 28.

The two wiper carriers 416 are supported on a slide 420 movable forwardly and rearwardly along guideways 422 (Fig. 3) on the frame, and each carrier is guided for movement about a central vertical axis indicated at *x* in Fig. 3 by means 50 of a tongue 424 (Fig. 25) which projects from the carrier into a groove 426 in the slide 420. The wiper carriers are confined on the slide 420 by a cover plate 428 fast on the slide. The slide 420 is moved forwardly to impart to the wipers their 55 advancing movements lengthwise of the shoe by a path cam 430 (Figs. 7, 18 and 22) in the cam drum 176, this cam engaging a roll 432 which is mounted on a rearward extension of the slide.

The means for imparting to the wipers their 60 closing movements, in the construction herein shown, acts independently of the means above described for imparting to them their forward or advancing movements. For this purpose there is pivotally connected to each of the wiper carriers 416, by means of a removable pin 434 (Fig. 3), a link 436 which has adjustably threaded in its rear end a member 438 pivotally mounted on a pin 440 in the forward end of a rack bar 442, this rack bar being mounted in a guideway in 65 the frame. The teeth of each rack bar 442 are engaged by the teeth of a gear sector 444 formed on a member 446 which turns about a pin 448 on the frame. Also formed on each member 446 are teeth 450 in engagement with teeth on a 70 75

central rack bar 452 (Figs. 3 and 7) adjustably secured, as will presently be described, to a slide 454 which is movable in guideways in the frame in directions lengthwise of the shoe. The 5 slide 454 carries a roll 456 engaged by a path cam 458 in the cam drum 176. It will thus be seen that rearward movement of the slide 454 serves to impart forward movements to the two rack bars 442 and thus through the links 436 10 to impart swinging movements to the wiper carriers 416 for closing the wipers laterally of the shoe. Such rearward movement of the slide 454 to close the wipers is substantially simultaneous with the forward movement of the slide 420 to 15 advance the wipers lengthwise of the shoe, and since these two movements are effected by different cams and are in opposite directions there is substantially no end thrust on the cam drum 176 and the shaft 178 in operating the wipers. 20 That is, the force tending to move the drum and the shaft in one direction in effecting the advancing movement of the wipers is substantially balanced by the force tending to move it in the opposite direction in effecting the closing of the 25 wipers. This not only minimizes wear, but also reduces the amount of power required to operate the machine.

As above stated, the rack bar 452 through which closing movements are imparted to the 30 wipers is adjustably secured to its operating slide 454. By its adjustment relatively to the slide 454 the wiper carriers and the wipers may be preliminarily adjusted toward or from each other about the axis of their closing movements 35 for shoes of different widths so as to determine the distances from the side edges of the heel seat at which the fastening tacks are driven. Threaded in the rack bar 452 is one end of a shaft 460 (Figs. 3 and 7) which is mounted to 40 turn in a bearing in the slide 454 and carries a pinion 462 in engagement with another pinion 464 mounted on a stud 466 on the slide 454. The shaft 460 is held against lengthwise movement in one direction relatively to the slide 454 45 by engagement of the pinion 462 with the slide, and against movement in the opposite direction by a member 468 threaded on the end of the shaft for engagement with the slide. The pinion 464 is in mesh with a pinion 470 mounted on a stud 50 50 472 on the frame, this pinion being sufficiently elongated to maintain contact with the pinion 464 during the operative movements of the slide 454. The pinion 470 is in mesh with a pinion 474 which is mounted on a stud 476 on the frame 55 and is connected to a sprocket wheel 478 on this stud. The sprocket wheel 478 is connected by a chain 480 to another sprocket wheel 482 mounted on a stud 484 which is adjustably secured (Fig. 4) to a bracket 486 on the frame. The 60 sprocket wheel 482 is connected by a chain 488 to a sprocket wheel 490 fast on a shaft 492 mounted in a bearing in the bracket 486 and also in a bearing near the front of the frame. The shaft 492 carries a pinion 494 (Fig. 7) which, 65 through an idle pinion 496, is connected to a pinion 498 (Fig. 4) fast on a shaft 500 mounted in a bearing in the frame. Fast on the forward end of this shaft is a hand crank 502 for turning it. It will thus be seen that by movement of the 70 crank 502 the wipers may be preliminarily adjusted toward or from each other as desired independently of any bodily movement thereof lengthwise of the shoe.

The hold-down 6 which determines the height 75 at which the shoe is presented in the lasting

operation has an upward extension 504 (Fig. 7) vertically movable in a guideway in the frame and provided with rack teeth in engagement with a pinion 506 formed integral with a shaft 508 (Fig. 14). Also integral with the shaft 508 is a spiral gear 510 which meshes with correspondingly formed rack teeth on a slide 512 connected by a coupling member 514 to a bar 516 the rear end of which is slidably mounted in a recess formed in a slide 518. The slide 518 is mounted 10 in a guideway in the frame and carries a roll 520 arranged to be engaged by a face cam 522 (Figs. 2 and 22) formed on the forward end of the cam drum 176. Mounted in a recess in the bar 516 is a light spring 524 which bears at its rear end 15 against the slide 518 and tends by its expansion to move the bar 516 forwardly and thus to lower the hold-down 6 by turning the shaft 508. Movement of the bar 516 in this direction is limited by means hereinafter described. When the operator raises the jack post 14 and the shoe by means of the treadle 98 prior to the starting of the machine he lifts the hold-down by contact of the shoe therewith and thereby forces the bar 516 rearwardly against the resistance of the 20 spring 524 until a lug 526 on the bar engages the slide 518. Thereafter, at the beginning of the power operation of the machine and substantially at the time when the jack is operated by the yielding means shown in Fig. 5 to press the 25 shoe more firmly back against the heel band, the cam 522 acts through the slide 518 and the bar 516 to impart a short downward movement to the hold-down and thus to depress the shoe in the heel band and cause the band to wipe the 30 upper smoothly against the last before the shoe is clamped with heavy pressure. In this operation the frictional contact of the shoe with the heel band also serves to return the band to its lowest position if it was previously raised as the 35 shoe was forced up by the treadle. The amount of such downward movement of the hold-down may be varied by adjustment of a member 528 (Fig. 14) which is slidably mounted in bearings in the frame and extends through a recess 530 40 in the slide 518, this member having a wedge face 532 arranged to engage a parallel face formed on the slide. It will be seen that by adjusting the member 528 inwardly the slide 518 may be moved in a direction to separate the roll 520 45 from its operating cam 522 against the resistance of the spring 524, so that less movement will be imparted to the slide by the cam and accordingly the hold-down will receive less downward movement. On the other hand, by adjusting the member 528 in an outward direction the 50 amount of downward movement imparted to the hold-down may be increased. The member 528 is adjusted by means of a screw 534 which is threaded therein and is held against lengthwise 55 movement by a member 536 which is threaded in the frame and is engaged on opposite sides respectively by a flange 538 and a collar 540 on the screw. A set screw 542 may be tightened to hold the member 528 securely in adjusted position. 60 It will be understood that while this adjustment serves to vary the amount of downward movement imparted to the hold-down, it does not effect any variation in the limit of such movement. For this purpose the hold-down is initially adjustable vertically by lengthwise movement of the shaft 508 which causes the shaft to turn by reason of the engagement of the teeth on the slide 512 with the spiral gear 510. For thus moving the shaft lengthwise there is threaded in 65 70 75 80 85 90 95 100

the frame a sleeve 544 which abuts at one end against the gear 510 and at the other end against a collar 546 fast on the shaft, the sleeve having thereon a knurled head 548 for turning it. The 5 sleeve is held in adjusted position by a spring-pressed detent 550 (Fig. 2) arranged to enter one or another of a plurality of slots formed in the sleeve. It will be understood that this adjustment of the initial position of the hold-down 10 serves also to determine adjustably the limit of its downward movement and thus to determine the height at which the heel seat is presented for the action of the wipers. The shape of the cam 522 is such that the hold-down is permitted 15 to rise slightly in response to upward pressure of the shoe against it between the first and second over-wiping movements of the wipers to cause an increased pressure of the wipers on the upper in their second over-wiping movement. 20 Thereafter the hold-down is depressed by the cam to force the shoe downwardly away from the wipers prior to the retractive movement of the latter, this operation taking place immediately after the opening of the heel band 25 and the release of the jack and the jack post by the mechanism controlled by the cam 174.

The tacks for fastening the heel end of the upper in lasted position are driven by a plurality of track drivers 552 (Figs. 7 and 25) movable in driver passages provided in the tacker blocks 404 in alignment with the openings 406 in the wipers, substantially as disclosed in the previously mentioned Letters Patent No. 1,852,-015. The drivers 552 in each tacker block are 30 secured at their upper ends to a curved driver block 554 movable in a similarly curved recess provided in the tacker block. Accordingly each driver block 554 is movable with the wipers as the latter are advanced and closed inwardly over the 35 shoe bottom. On the upper end of each driver block 554 is a stud 556 which is located in a slot formed in an inverted T-shaped operating member 558 and has a head 560 overlapping the member 558 so that this member in its upward movement serves to retract the drivers. The member 40 558 is pivotally mounted on a pin 562 which is supported in the lower forked end of a link 564, and the upper end of this link is pivotally mounted on a pin 566 supported on the forward 45 end of a driver-operating lever 568. At its rear end the lever 568 is pivotally supported on a short link 570 which is pivoted on the frame of the machine. Accordingly the drivers are operated to drive the tracks by downward swinging 50 movement of the lever 568 about its connection with the link 570, the lever acting on the drivers through the link 564 which may swing forwardly and rearwardly to maintain an operative relation to the driver blocks 554 in all positions of 55 the wipers.

The driver-operating lever 568 is controlled by a cam 572 (Figs. 7 and 15) fast on the forward end of the shaft 178. This cam acts to raise the lever through a plunger 574 vertically movable 60 in a bearing in the frame and pivotally connected at its upper end to the lever, the plunger having at its lower end a roll 576 engaged by the cam. It will be understood that when the high point of the cam passes the roll the plunger 574 is suddenly released to permit the lever 568 to swing 65 downwardly and operate the tack drivers. For imparting such downward movement to the lever 568 there are provided, in the construction herein shown, two comparatively light springs 578, and also two comparatively heavy springs 580 70 which under certain conditions, as hereinafter explained, act on the lever in addition to the light springs. Each of the light springs 578 acts on the lever 568 through a rod 582 pivotally connected at its upper end to the lever and extending downwardly through a thimble 584 threaded in the frame. The spring 578 abuts at its upper end against this thimble and at its lower end against a washer 586 confined by nuts on the rod 582. By adjustment of the thimble 584 upwardly or downwardly in the frame the stress of the spring 578 may be varied. Each of the heavy springs 580 acts on the lever 568 through a bar 588 guided for vertical movements in a bearing in the frame, the spring abutting at its upper end against the frame and at its lower end against a washer 590 confined by nuts 592 on the bar. At its upper end each of the bars 588 acts on the lever 568 through a shaft 594 which is carried by the lever and extends through vertical slots 20 596 in the upper end portions of the bars. It will thus be seen that when the lever 568 is released by the cam 572 it may be impelled downwardly to operate the drivers both by the light springs 578 and by the heavy springs 580. 25

For driving tacks fully into the shoe materials and clinching them on the usual metal heel plate of the last both the light springs and the heavy springs are utilized to operate the lever 568; but if the machine is operated without any shoe on 30 the jack, as may be done for test purposes, the light springs alone are utilized so as to reduce the force of impact of stop mechanism hereinafter described for limiting the movement of the lever. To bring this about there is provided mechanism 35 controlled by each shoe for rendering the heavy springs operative only when there is a shoe on the jack. This mechanism includes a shaft 598 (Figs. 7 and 15) mounted to turn in a bearing in the frame and arranged to extend normally into 40 curved recesses provided in the bars 588, as illustrated in Fig. 7, so as to lock these bars against downward movement. The shaft, however, is provided with recesses 600 adjacent to the bars 588, so that when turned a certain distance it will 45 clear the bars and permit the latter to be forced downwardly by the springs 580 when the lever 568 is released by the cam 572. Such turning movement of the shaft 598 is effected by a torsion spring 602 (Fig. 15) and is limited by contact 50 of a lug 604 (Fig. 16) on the shaft with a pin 606 mounted in a bracket 608 on the frame. The shaft 598 is normally held against the resistance of the spring 602 in the locking position in which it is shown in Figs. 7 and 15 by means of a lever 55 610 (Figs. 2 and 15) which is pivotally mounted on a pin 612 on the bracket 608 and is controlled by the previously mentioned bar 516 connected to the hold-down 6. The upper end of the lever 610 is connected to a crank pin 614 (Fig. 16) on 60 the shaft 598 by a link 616, and at its lower end the lever has mounted therein a plunger 618 (Fig. 14) arranged to engage a lug 620 on the bar 516. The plunger 618 is backed up by a spring 622 and has a stem 624 extending outwardly through the lever 610 and provided with nuts 626 for limiting movement of the plunger under the influence of the spring. Near its upper end the lever 610 normally engages a stop lug 628 (Fig. 2) 70 on the frame. By reason of the engagement of the lever 610 with the lug 628, and because of the fact that the spring 622 is stronger than the spring 524 in the bar 516, the plunger 618 serves to limit movement of the bar 516 toward the right 75

(Fig. 14) and thus to limit the downward movement of the hold-down 6 when there is no shoe in the machine. The spring 602 which turns the shaft 598 is a lighter spring than either of the 5 springs 524 and 622, and accordingly the shaft is maintained normally in locking relation to the bars 588 by the action of the lug 620 on the plunger 618. If the machine, therefore, is run without any shoe on the jack, the heavy springs 10 580 are prevented from operating, since the hold-down is not lifted by any shoe and the lever 610 is maintained continuously by the lug 620 in position to prevent the spring 602 from turning the shaft 598. It will be understood that under these 15 conditions the shaft 594 moves along the slots 596 in the bars 588. On the other hand, if a shoe is mounted on the jack the lifting of the hold-down by the action of the shoe thereon when the operator depresses the treadle 98 results in 20 such release of the lever 610 by the lug 620 as to permit the shaft 598 to be turned by the spring 602 into position to unlock the bars 588. Accordingly 25 the heavy springs 580 will act in conjunction with the light springs 578 to operate the tack drivers. When the bar 516 is operated positively by the slide 518 to lower the hold-down and depress the shoe near the end of the cycle of operations after the tacks have been driven, the lug 620 acts on the lever 610 to return the shaft 30 598 to its locking position, any excess movement of the bar after the lever 610 is stopped by the lug 628 resulting in movement of the plunger 618 against the resistance of its spring 622. It will be understood that when the parts have all 35 resumed their normal positions the spring 524, through the bar 516, maintains the lever 610 against the lug 628.

There is further provided means whereby the shaft 598 may be maintained in position to prevent the heavy springs 580 from acting, even 40 though the machine is operating on a shoe. This means comprises a plunger 630 (Fig. 15) slidably mounted in the lever 610 and arranged to enter a bore 632 in the bracket 608. A spring 634 in 45 the lever tends to force the plunger into this bore, but is normally prevented from doing so by a member 636 which is fast on a stem 638 extending outwardly from the plunger and has two fingers 639 arranged to enter shallow recesses in the 50 end of a boss 640 on the lever 610, as shown in Fig. 15. Integral with the member 636 is a knurled head 642 by means of which the member may be turned into position to permit the fingers 639 to enter diametrically opposite slots 55 644 in the boss 640, thus permitting the plunger 630 to be forced into the bore 632 by the spring 634. Under these conditions the lever 610 is locked against swinging movement under the influence of the spring 602, so that the shaft 598 will 60 be maintained in its locking position throughout the operation of the machine. Accordingly the driver-operating lever 568 will be operated only by the light springs 578, as may be desired in driving the tacks only part way into a shoe in lasting 65 with adhesive.

In order to limit the operative movements of the tack drivers the driver-operating lever 568 carries a stop member 646 arranged to engage leather washers 648 mounted in a recess in the frame. The member 646 has an upstanding lug 650 extending into a slot 652 in the lever 568 and mounted on an eccentric 654 formed on a cylindrical member 656 which is mounted in a bearing 70 in the lever 568 and through which the previous-

ly mentioned shaft 594 extends. This shaft is keyed to the member 656 and is provided at one end with a square portion 658 whereby the shaft and the member 656 may be turned to adjust the stop member 646 downwardly or upwardly. For 5 holding the member 656 in adjusted position there is provided a latch 660 (Figs. 15 and 32) which is pivoted on the lever 568 and is arranged to enter one or another of a plurality of notches 662 formed in a flange on the member 656. It 10 will be understood that by the adjusting means thus provided the member 646 may be variably positioned to determine how far the tacks will be driven into the shoe, and it may be so positioned that the tacks will be left upstanding 15 (Fig. 31) in lasting with adhesive. In order to prevent the member 646 from turning about the eccentric 654 in the operation of the machine, there is mounted in a recess in the lever 568 a 20 plunger 664 pressed down by a spring 666 and arranged to engage a flat face on the upper end of the lug 650.

The tacks are supplied to the driver passages through flexible tubes 668 connected to the tacker blocks 404 as illustrated in Fig. 25, these tubes 25 leading from a tack separator 670 (Fig. 2) associated with an oscillatory tack hopper 672. This tack-supplying mechanism is not herein shown in detail, since it is constructed substantially as heretofore in machines of the illustrated type, 30 the main characteristic features thereof being disclosed, for example, in Letters Patent No. 1,129,882, granted on March 2, 1915 upon an application of R. F. McFeely. It will be understood that the tack separator and the tack hopper are 35 operated by oscillatory movements of a shaft 674 effected by a vertically movable rack bar 676. This rack bar, in the construction herein shown, is connected by a link 678 to an operating lever 40 680 (Figs. 7 and 12) mounted on the hub of another lever 682 which is mounted on a rod 684 on the frame. A detent 686 in the lever 680 normally extends into a recess in the lever 682 to connect the two levers for movements in unison. At its rear end the lever 682 is provided with a gear 45 sector 688 in engagement with teeth formed on a vertically movable slide 690 which is mounted within another slide 692 movable in a vertical guideway in the frame. The slide 692 carries a roll 694 (Fig. 7) engaged by a path cam 696 50 formed in a cam wheel 698 which turns with the shaft 178. The slide 692 is connected yieldingly to the slide 690 through a spring 700 which is mounted in the slide 690 about a rod 702, this rod being fastened at its upper end to the slide 55 692 by a pin 703 so as to move at all times with this slide. The spring 700 at its lower end abuts against a washer 704 confined by nuts on the rod 702 and arranged to bear downwardly on a shoulder on the slide 690. At its upper end the 60 spring abuts against a washer 706 which seats against a diametrically enlarged upper portion of the rod 702 and is arranged to bear upwardly against a thimble 708 which is threaded in the slide 690 and through which the rod 702 may 65 slide. It will thus be seen that when the slide 692 is operated by its cam 696 it acts though the rod 702 and the spring 700 to transmit movement yieldingly in both directions to the slide 690 for oscillating the shaft 674.

The lever 682 serves additionally through a link 710 (Figs. 7 and 12) to operate a piston 712 of an oil pump 714 whereby lubricating oil is forced from a reservoir 716 to a higher reservoir (not shown) from which it flows by gravity through 75

various conducting tubes to the different parts of the machine which require lubrication. Under some conditions it may be desired to operate the machine on shoes without driving any tacks at all, as in lasting with adhesive of such character as to require no temporary holding tacks; and to permit this to be done without interfering with the operation of the oil pump the detent 686 (Fig. 12) is movable at the will of the operator to disconnect the lever 680 from the lever 682 and thus to prevent the operation of the tack separator while the lever 682 continues to operate the pump. For this purpose the detent carries a pin 718 connected by a link 720 to an eccentric 722 which is fast on a shaft 724 mounted in a bearing in the frame. Splined on the shaft 724 (Fig. 13) for sliding movement lengthwise thereof against the resistance of a spring 726 is a knob 728 by which the shaft may be turned to withdraw the detent 686 from engagement with the lever 682 or to permit the detent to be returned to its normal operating position by a spring 730 when the parts are in their starting positions. The knob 728 carries a pin 732 arranged to enter a recess 734 in the frame for locking the detent in operative position or to enter a recess 736 to lock it in its inoperative position.

The machine is further provided with means of substantially the same construction as disclosed in Letters Patent No. 1,901,167, granted on March 14, 1933 upon an application of mine, for preventing the shaft 674 (Fig. 2) from turning far enough to cause separation and delivery of tacks, without interfering with the operation of the tack drivers, in case, for example, it may be desired to run the machine idly one or more times to remove an obstruction from some one of the driver passages, and which may be utilized also by further movement to prevent additionally the movements of the tack drivers if it is desired to run the machine without driving any tacks. Briefly, this means comprises a lever 738 (Figs. 2 and 7) movable into position for its upper end to be engaged by a lug 740 on the track hopper 672 to limit movement of the hopper and the shaft 674 and connected at its lower end to a slide 742 which is movable into position under a lug 744 on the plunger 574 to prevent movement of the driver-operating lever 568. The lever 738 is operated by a hand lever 746 extending forwardly to a position within convenient reach of the operator. If it should be desired to operate on shoes without the use of tacks, this mechanism will preferably be utilized to prevent the movements of the tack drivers, and the lever 680 also will be disconnected from the lever 682 in the manner hereinbefore described so as to prevent the lug 740 on the track hopper from bumping against the lever 738 as it would if this were the means depended upon to prevent the delivery of tacks.

The machine herein shown is driven by an electric motor 748 (Figs. 1 and 2), although it will be understood that it may be driven by other means. The motor is connected by a belt 750 to a pulley 752 (Fig. 10) so mounted as to permit it to turn about a sleeve 754 which is keyed to a shaft 756 mounted in bearings in the frame. The pulley is so formed as to serve as one of the cooperating members of a friction clutch, the other clutch member 758 being mounted on the sleeve 754 for movements lengthwise of the sleeve and being permanently connected to the sleeve to turn therewith by means of fingers 760 which project

from the sleeve into openings in the member 758. A spring 762 bearing at one end on the hub of the clutch member 758 and at the other end against a bushing 764 which is threaded on the sleeve 754 serves, when permitted, to move the clutch member 758 into clutching engagement with the pulley 752 to cause the shaft 756 to be driven by the pulley. When the shaft is thus driven it operates the previously mentioned shaft 178 through a worm 766 which is fast on the shaft 10 756 and engages a worm gear 768 fast on the shaft 178. By reference to Fig. 7 it will be seen that the previously mentioned cam wheel 698 is secured to this worm gear 768.

For controlling the clutch member 758 there is 15 provided a bell-crank lever 770 mounted as hereinafter described and provided with upwardly extending arms 772 (Fig. 11) which carry pins 774 on which is pivotally mounted a yoke member 776 fitting in a groove formed in the hub of the clutch member 758. The bell-crank lever 770 is further provided with a substantially horizontal arm 778 (Figs. 7, 10 and 23) on which is pivotally mounted a block 780 which lies in a horizontal guideway provided by two flanges 782 on a slide 784, this 20 slide being vertically movable in a guideway in the frame. It will thus be seen that the bell-crank lever 770 is controlled by the slide 784 and that when this slide is in one position it acts through the bell-crank lever to hold the clutch member 30 758 out of engagement with the pulley 752, as illustrated in the drawings. For maintaining the slide 784 normally in this position there is provided another slide 786 vertically movable in the same 35 guideway as the slide 784 and carrying a roll 788 engaged by a path cam 790 formed in the cam wheel 698. Fast on the slide 786 is a plate 792 arranged to engage the upper end of a finger 794 which is pivotally mounted on a pin 796 in the slide 784. A spring 798 (Fig. 7) carried by the slide 784 tends to hold the finger 794 against one face of the slide 784 with its upper end in position to be engaged by the lower edge of the plate 792. By engagement of the plate 792 with the upper end 40 of the finger when the latter is in this position the slide 786 serves normally to hold the slide 784 in a depressed position such that the clutch member 45 758 is held out of engagement with the pulley 752.

For releasing the clutch member 758 to permit it to be forced by the spring 762 into engagement with the pulley 752 there is provided means for swinging the finger 794 rearwardly from beneath the plate 792 so as to permit upward movement of the slide 784 in response to the action of the spring 762. This means comprises an arm 800 pivotally mounted on the rear end of a rod 802 which is movable lengthwise in a bearing in the frame, this rod carrying a spring 804 which holds the rear end of the arm 800 normally up against a shoulder on the frame in a location immediately in front of the upper end portion of the finger 794. It will thus be seen that when the rod 802 is moved rearwardly it causes the arm 800 to swing the finger 794 out from under the plate 792, thus releasing the slide 784 for upward movement. It will be understood that by such upward movement of the slide 784 the upper end portion of the finger 794 is carried upwardly along the rear face of the plate 792. In this operation a recess 806 (Fig. 23) 55 in the finger 794 arrives opposite the end of the arm 800 to permit the latter to enter the recess. 60

For imparting to the rod 802 its rearward movement to start the machine as above described there is provided a push rod 810 (Figs. 4 and 7) 65 70 75

mounted in a bearing in the front of the frame and provided on its forward end with a rubber pad 812 to be engaged by the hand of the operator. At its rear end the push rod 810 is threaded 5 in another rod 814 mounted in a bearing in the frame, this rod having thereon a spring 816 which bears at one end against a web 818 on the frame and at its other end against a collar 820 fast on the rod 814. The rod 814 has a pin-and-slot 10 connection with one end of a lever 822 which is pivotally mounted on the frame at its other end, and this lever is connected by a link 824 to the rod 802. It will thus be seen that to start the machine the operator imparts a rearward movement 15 to the push rod 810 against the resistance of the spring 816 and that when the operator releases the push rod the spring returns it to its starting position, thus withdrawing the arm 800 from contact with the finger 794. A head 826 on 20 the rod 802, on which the arm 800 is pivoted, serves by engagement with the frame to limit return movement of the parts controlled by the spring 816.

After the machine has been started as above 25 described the cam 790 acts to raise the slide 786 far enough to permit the finger 794 to be swung by its spring 798 again into position under the plate 792. Thereafter, substantially at the end 30 of the cycle of operations, the slide 786 is moved downwardly by the cam 790 and acts on the finger 794 to move the slide 784 also downwardly and thus to withdraw the clutch member 758 from engagement with the pulley 752. Even if the operator has not released the push rod 810, the 35 machine will nevertheless be stopped automatically in this manner at the end of the cycle, by reason of the fact that the arm 800 projecting into the recess 806 of the finger 794 is ineffective to prevent return of this finger into position 40 under the plate 792.

Also controlled by the slide 784 is a brake which 45 assists in stopping the machine at the end of the cycle. This brake comprises a wheel 828 (Figs. 2 and 10) fast on the shaft 756 and engaged on its periphery by a band 830. This band is anchored 50 at one end to the frame and is adjustably connected at its other end to an arm 832 fast on a shaft 834. Also fast on the shaft 834 is an arm 836 (Figs. 7 and 23) connected by a link 838 to the same pin 796 on the slide 784 on which the finger 794 is mounted. It will thus be seen that 55 when the slide 784 is depressed to stop the machine the shaft 834 is turned in the direction to tighten the brake band 830, and when it is raised in the starting of the machine the shaft is turned 60 in the opposite direction to loosen the brake band.

As a matter of safety, there is further provided 65 means for preventing the starting of the machine even though the push rod 810 is operated accidentally or otherwise, and this means serves further to permit the release of the brake without such actuation of the clutch as to start the machine so as to permit the machine to be operated by hand, if desired, through a hand wheel 840 fast on the shaft 756. This means comprises an eccentric 842 (Figs. 10 and 11) supporting the bell-crank lever 770 which controls the clutch and the brake, the eccentric being part of a shaft 844 mounted to turn in bearings in the frame. 70 This shaft is held against lengthwise movement by a stud 846 projecting into a peripheral slot 848 in the shaft, and fast on its outer end is a crank arm 850 for turning it. The crank arm 850 carries a spring-pressed plunger 852 (Fig. 7) arranged 75 to enter one or the other of two holes 854 and 856

(Fig. 10) in the frame, this plunger being connected to a knob 858 for withdrawing it from either of these holes. Normally the eccentric 842 is maintained in a position determined by the plunger 852 in the hole 854. If it is desired to 5 render the starting means inoperative to start the machine the plunger 852 is withdrawn from the hole 854 and the crank arm 850 is lifted until the plunger is permitted to enter the hole 856. The eccentric 842 is thus turned in such manner 10 as to move the bell-crank lever 770 bodily toward the left (Fig. 10) to carry the clutch member 758 farther away from the pulley 752 against the resistance of the spring 762, the block 780 sliding along its guideway in the slide 784. If the push 15 rod 810 is operated to disconnect the finger 794 from the plate 792 with the parts in these positions, a block 860 (Fig. 7) carried by the slide 784 engages a block 862 fast on the frame and thus 20 stops the upward movement of the slide 784 before the clutch member 758 has been moved far enough to engage the pulley 752. Accordingly the push rod 810 is ineffective to start the machine. By such upward movement of the slide 784, however, the brake is released, so that the 25 machine may be operated by hand if desired. It will be understood that in such operation of the machine the slide 784 is eventually moved downward to its starting position, as usual, by the action of the slide 786 on the finger 794. It will 30 be further understood that if it should be desired to operate or to complete the operation of the machine by power instead of manually after the ineffective movement of the push rod 810, it is only necessary to return the eccentric 842 to its 35 initial position by movement of the crank arm 850, thus causing the clutch member 758 to engage the pulley 752.

Such adjustments of the clutch member 758 as 40 may be desirable at any time to improve the efficiency of the clutch may be effected by turning the shaft 844 relatively to the crank arm 850. For this purpose there are provided set screws 864 threaded in the hub of the crank arm and arranged to bear oppositely against flattened surfaces provided on the shaft 844 at one side of the axis of the shaft. The crank arm 850 is held in place on the shaft by a screw 866 which is threaded in the end of the shaft.

In Figs. 29 and 30 is shown a work support or 45 jack so constructed as to adapt it to receive long-legged boots. Parts of this structure which are substantially identical with those shown in Figs. 2 and 19 are designated by the same reference characters. In the construction shown in Fig. 29 there is a holder 868 for the post 14, similar to the holder 34 of the other construction shown in Figs. 2 and 19 but integral at its lower end with a casting 870 corresponding to the casting 46 of the other construction. Slidably movable in the 50 holder 868 is a member 872 similar to the member 60 of the other construction and similarly supporting the post 14 with provision for a stepped upward or downward adjustment of the post. The member 872 has in its upper end a screw 874 55 which rests on the upper end of a slidable rod 876, this rod corresponding in function to the rod 72 of the other construction and being connected to the slide 76. Fast on the rod 876 in a location low enough to clear the leg of any boot is a forwardly extending arm 878 movable with the rod 65 upwardly and downwardly in a recess in the casting 870, and connected to the forward end of the arm 878 is a rod 880 parallel to the rod 876 and the post 14 and slidably movable in bearings pro- 70 75

vided in forward extensions 882 and 884 of the casting, these extensions being forked near the holder 868 to clear the leg of a boot. The upper end portion of the rod 880 is enlarged and is 5 bored to receive another rod 886 on the upper end of which is mounted means for supporting the forepart of the boot. This means comprises a toe rest 888 curved for a considerable distance about the axis of the heel pin 8 for supporting on different portions thereof the foreparts of right and left boots, since this forepart support is not movable laterally about the axis of the post 14 as is the corresponding support in the construction 10 shown in Figs. 2 and 19. The toe rest 888 is secured to a casting 890 which by mechanism of substantially the same construction as shown in Fig. 2 is adjustable in upward and downward directions relatively to a slide 892 supported on an arm 894 fast on the rod 886. The slide 892 is 15 adjustable along the arm 894 for shoes of different lengths and is held in adjusted position by pawls 896 engaging teeth 898 on the opposite sides of the arm. To accommodate lasts that vary substantially in height, there is provision for a 20 stepped upward or downward adjustment of the rod 886 and the parts supported thereon relatively to the rod 880, corresponding to the similar adjustment of the post 14 relatively to the member 872. For this purpose there is rotatably 25 mounted on the rod 886, between the arm 894 and a head 900 on the upper end of the tubular portion of the rod 880, a collar 902 having therein a plurality of recesses 904 of different heights arranged to receive a finger 906 extending upwardly 30 from the head 900. To effect the adjustment the rod 886 and the parts supported thereon are lifted, the collar 902 is then lifted and turned by use of a handle 908 thereon to bring the proper recess 904 therein into alignment with the finger 906, 35 after which the collar and the rod 886 are lowered. It will be understood that in the operation of the machine when equipped with this boot support the toe rest 888 is lifted with the post 14 by the lever 108, since the rods 876 and 880 are connected 40 together in fixed relation to each other by the arm 878.

In the operation of the machine the operator mounts a shoe on the jack and, if necessary, adjusts the heel band in accordance with the width 50 of the shoe and adjusts the forward ends of the band to the right or the left so that the band when it closes will properly position the heel end of the shoe laterally in relation to the wipers. The wipers also may be adjusted toward or from 55 each other, if necessary, in accordance with the width of the shoe. The operator thereafter, by use of the treadle 98, swings the jack rearwardly to carry the shoe against the heel band and forces the shoe upwardly against the holddown 6, 60 controlling the shoe with his hands to insure that it is not forced upwardly until near the end of its rearward movement. The holddown is forced upwardly by the shoe as far as permitted by the lug 526 (Fig. 14) and by this movement releases 65 the means which unlocks the two bars 588 and the heavy springs 580 so that their force will supplement the force of the lighter springs 578 when the driver-operating lever 568 is released to drive the tacks. The operator then starts the machine, 70 whereupon the jack is swung farther rearwardly to press the shoe more firmly against the heel band by the yieldable means shown in Fig. 5. By the pressure of the shoe on the heel band the latter is forced rearwardly against the abutment 75 246 (Fig. 8), the plungers 270 being forced out-

wardly by the band against the resistance of their controlling springs and serving to press the band firmly against the corners of the heel end of the shoe. At substantially the same time the holddown 6 receives a short downward movement 5 from its controlling cam and depresses the shoe with the jack post 14 to the proper level for the first operation of the wipers, thus causing the heel band to wipe the upper upwardly toward the edge of the heel seat around the rear-end face 10 of the shoe and insuring that the heel band will occupy its lowest position on its support.

Immediately after these operations the cam 174 becomes effective through the positively acting means described to force the shoe still more firmly 15 back against the heel band through the jack, this cam acting also to close the heel band yieldingly against the sides of the shoe and to force the shoe more firmly up against the holddown through the post 14. As the shoe is thus forced upwardly the spring 144 (Fig. 19) may yield more or less. The wipers are then advanced and closed to wipe the margin of the upper materials over the heel seat, after which they are retracted from over the heel seat. At this point the cam 522 controlling the 20 holddown permits the shoe to be raised to a slightly higher level by the action of the spring 144 on the post 14, and the cam 174 is further effective to force the shoe still more firmly back 25 against the heel band, to force the heel band more firmly against the sides of the shoe and to increase the force with which the shoe is pressed up against the holddown. The wipers are then advanced and closed a second time, whereupon 30 the spring-impelled lever 568 is released to drive the tacks through the openings in the wipers. Thereafter the shoe is released from the pressure of the jack and the heel band, the holddown 6 is moved downwardly to depress the shoe, and the wipers are then retracted from over the heel 35 seat, all parts returning to their starting positions.

If it is desired to drive the tacks only partially into the shoe in case, for example, an adhesive 40 is used to fasten the upper materials permanently 45 in lasted position, the operator turns the eccentric 654 (Fig. 15) to adjust the stop member 646 so that the driver-operating lever 568 will receive a shorter movement. By means of the plunger 630 he also locks the shaft 598 from turning during the operation of the machine so as to prevent the heavy springs 580 from acting on the lever 568. The tacks are accordingly driven only by the action of the light springs 578. It will be 50 understood that the depression of the shoe by the holddown before the wipers are retracted is sufficient to withdraw the upstanding tacks from the 55 openings in the wipers.

It is to be understood that the term "shoe" as used herein, unless the context requires a different interpretation, is not intended to exclude what may be more properly termed a boot supported, for example, on a jack of the construction shown in Fig. 29.

Having described the invention, what I claim 60 as new and desire to secure by Letters Patent of the United States is:

1. In a lasting machine, the combination with end-lasting wipers, of mechanism for advancing said wipers lengthwise of a shoe, mechanism for closing the wipers laterally of the shoe, a cam shaft, a cam on said shaft for operating said wiper-advancing mechanism by force applied in one direction lengthwise of the shaft, and another cam on said shaft for operating said wiper- 70 75

closing mechanism by force applied in the opposite direction lengthwise of the shaft.

2. In a lasting machine, the combination with 5 end-lasting wipers, of mechanism for advancing said wipers lengthwise of a shoe, mechanism for closing the wipers laterally of the shoe, and a rotatable cam member provided with a cam for operating said wiper-advancing mechanism by force applied in one direction lengthwise of the 10 axis of the cam, said cam member being provided with another cam for operating said wiper-closing mechanism by force applied in the opposite direction lengthwise of said axis.

3. In a lasting machine, the combination with 15 end-lasting wipers, of a member movable in one direction to advance said wipers lengthwise of a shoe, another member movable in the opposite direction to close the wipers laterally of the shoe, and a pair of coaxial cams for operating said 20 members by forces applied thereto respectively in opposite directions lengthwise of the axis of the cams.

4. In a lasting machine, the combination with 25 end-lasting wipers, of a member movable in one direction to advance said wipers lengthwise of a shoe, another member movable in the opposite direction to close the wipers laterally of the shoe, and a cam shaft extending lengthwise of the paths of movement of said members and having 30 thereon cams for operating the members.

5. In a lasting machine, the combination with 35 end-lasting wipers, of a slide movable in one direction to advance said wipers lengthwise of a shoe, another slide movable in the opposite direction to close the wipers laterally of the shoe, each of said slides having a roll thereon, and a cam member rotatable about an axis extending lengthwise of the paths of movement of said 40 slides and provided in its periphery with path cams for engaging said rolls to operate the slides.

6. In a lasting machine, the combination with 45 a shoe support and end-lasting wipers, of a slide rectilinearly movable in a direction toward a shoe on said support to advance the wipers lengthwise of the shoe, and another slide rectilinearly movable in a direction away from the shoe to close the wipers laterally of the shoe.

7. In a lasting machine, the combination with 50 end-lasting wipers, of a pair of cam-operated slides in alinement with each other and operatively movable respectively in opposite directions, one of said slides being arranged to advance the wipers lengthwise of a shoe, and connections between the other slide and the wipers for closing 55 the wipers laterally of the shoe.

8. In a lasting machine, the combination with 60 end-lasting wipers, of a slide supporting said wipers and rectilinearly movable in a direction to advance them lengthwise of a shoe, and another slide rectilinearly movable in substantially the opposite direction and connected to the wipers for closing them laterally of the shoe by its movement in that direction.

9. In a lasting machine, the combination with 65 a shoe support and end-lasting wipers, of a slide movable in a direction toward a shoe on said support to advance the wipers lengthwise of the shoe, another slide movable in a direction away from the shoe to close the wipers laterally of the shoe, links for imparting to the wipers their closing movements by the operation of said other slide, and rack-and-gear mechanism for connecting the links to said other slide.

75 10. In a lasting machine, the combination with

end-lasting wipers, of a member movable in one direction to advance the wipers lengthwise of a shoe, another member movable in substantially the opposite direction to close the wipers laterally of the shoe, and connections between said other member and the wipers including a device common to both wipers for adjusting them simultaneously toward or from each other prior to their operative movements.

11. In a lasting machine, the combination with 10 a shoe support and end-lasting wipers, of a member supporting said wipers and movable in a direction toward a shoe on said support to advance the wipers lengthwise of the shoe, another member movable in a direction away from the 15 shoe to close the wipers laterally of the shoe, and connections between said other member and the wipers including a device common to both wipers for adjusting them simultaneously toward or from each other prior to their operative movements.

12. In a lasting machine, the combination with 20 end-lasting wipers, of a pair of cam-operated slides in alinement with each other and operatively movable independently of each other, one of said slides being arranged to advance the 25 wipers lengthwise of a shoe, connections between the other slide and the wipers for closing the wipers laterally of the shoe, and a member operative through said connections to adjust the 30 wipers simultaneously toward or from each other prior to their operative movements.

13. In a lasting machine, the combination with 35 a shoe support and end-lasting wipers, of a cam-operated slide movable in a direction toward a shoe on said support to advance the wipers lengthwise of the shoe, another cam-operated slide movable in a direction away from the shoe to close the wipers laterally of the shoe, a device 40 movable with said last-named slide and connected to the wipers for closing them, and means for adjusting said device relatively to the slide with which it is movable to effect an adjustment of the wipers simultaneously toward or from 45 each other.

14. In a lasting machine, the combination with 50 end-lasting wipers, of a member movable to advance the wipers lengthwise of a shoe, another member movable independently of said first-named member to close the wipers laterally of the shoe, a device movable with said last-named member and having two sets of rack teeth thereon, gear members meshing respectively with the different sets of rack teeth, rack bars connected to the wipers and operated by said gear members, and means for adjusting said device relatively to the member with which it is movable to effect an adjustment of the wipers simultaneously toward or from each other.

15. In a lasting machine, the combination with 60 end-lasting wipers, of a member movable to close said wipers laterally of a shoe, a device movable with said member and connected to the wipers for closing them, means comprising a pinion carried by said member for adjusting said device to effect an adjustment of the wipers toward or from each other, and another pinion supported independently of said member and meshing with said first-named pinion for operating the latter, the two pinions being constructed and arranged to maintain operative engagement with each other during the closing of the wipers.

16. In a heel-end lasting machine, the combination with heel-lasting wipers for operating on 75

- right and left shoes, of a heel band for embracing the heel end of a right or a left shoe to position the shoe in proper relation to the wipers, and means for adjusting said heel band for right and left shoes comprising a member movable by the operator to adjust both the forward ends of the band simultaneously in the same direction to the right or the left relatively to the wipers and relatively to the rear end of the band. 5
- 10 17. In a heel-end lasting machine, the combination with heel-lasting wipers for operating on right and left shoes, of a heel band for embracing the heel end of a right or a left shoe to position the shoe in proper relation to the wipers, 10 means for holding the rear end of said heel band against lateral movement, and means connected to the forward end portions of the heel band for adjusting the band for right and left shoes while its rear end is thus held, said adjusting means comprising a member movable by the operator to adjust both the forward ends of the band simultaneously in the same direction to the right or the left relatively to the wipers. 15
- 15 18. In a heel-end lasting machine, a heel band for embracing the heel end of each shoe, means comprising bell-crank levers connected to the forward end portions of said band for closing the band laterally of a shoe, and band-adjusting mechanism comprising a member movable by the operator and arranged to act through said bell-crank levers to adjust both the forward ends of the band simultaneously in the same direction to the right or the left relatively to the rear end of the band. 20
- 20 19. In a heel-end lasting machine, a heel band for embracing the heel end of each shoe, members connected to the forward end portions of said band and mounted for swinging movements to close the band laterally of a shoe, other members movable in unison in the same direction lengthwise of the shoe to operate said swinging members, and a device connected to said other members for moving them respectively in opposite directions to adjust both the forward ends of the heel band simultaneously in the same direction to the right or the left laterally of the shoe to position the band differently for right and left shoes. 25
- 25 20. In a heel-end lasting machine, a heel band for embracing the heel end of each shoe, members connected to the forward end portions of said band and mounted for swinging movements to close the band laterally of a shoe, other members movable in unison in the same direction lengthwise of the shoe to operate said swinging members, and a device connecting said other members together to prevent them from moving relatively to each other in the closing of the band, said device being movable by the operator to effect a preliminary adjustment of said other members respectively in opposite directions to adjust both the forward ends of the band simultaneously in the same direction to the right or the left relatively to the rear end of the band. 30
- 30 21. In a heel-end lasting machine, a heel band for embracing the heel end of each shoe, bell-crank levers connected to the forward end portions of said band for closing the band laterally of a shoe, rack bars connected respectively to said bell-crank levers and movable in unison in the same direction to close the band, a rotatable member connecting said rack bars together and movable bodily with them, means for holding said rotatable member against rotation to prevent relative movement of the rack bars in the 35
- 35 closing of the band, and means for turning said member to effect an adjustment of said rack bars respectively in opposite directions and thereby to adjust both the forward ends of the heel band simultaneously in the same direction to the right or the left. 40
- 40 22. In a heel-end lasting machine, a heel band for embracing the heel end of each shoe, band-adjusting mechanism comprising a member movable to adjust both the forward ends of said band simultaneously in the same direction to the right or the left relatively to the rear end of the band, and additional band-adjusting mechanism comprising a member movable to adjust both the forward ends of the band simultaneously toward or from each other. 45
- 45 23. In a heel-end lasting machine, a heel band for embracing the heel end of each shoe, operating mechanism for closing said band about the heel end of a shoe, a manually operated member for effecting relative movement of parts of said operating mechanism to adjust both the forward ends of the band simultaneously in the same direction to the right or the left, and another manually operated member for effecting relative movement of parts of said operating mechanism to adjust both the forward ends of the band simultaneously toward or from each other. 50
- 50 24. In a heel-end lasting machine, a heel band for embracing the heel end of each shoe, members connected to the forward end portions of said band and mounted for swinging movements to close the band laterally of a shoe, other members movable in unison in the same direction lengthwise of the shoe to operate said swinging members, and means for effecting a preliminary adjusting movement of said other members either in the same direction to vary the distance between the forward ends of the band or in opposite directions respectively to shift the forward ends of the band simultaneously to the right or the left. 55
- 55 25. In a heel-end lasting machine, a heel band for embracing the heel end of each shoe, members connected to the forward end portions of said band and mounted for swinging movements to close the band laterally of a shoe, other members movable in unison in the same direction lengthwise of the shoe to operate said swinging members, a device connected to said other members for imparting to them a preliminary adjusting movement in the same direction to vary the distance between the forward ends of the band, and another device connected to said other members for adjusting them respectively in opposite directions to shift the forward ends of the band simultaneously to the right or the left laterally of the shoe. 60
- 60 26. In a heel-end lasting machine, a heel band for embracing the heel end of a shoe, bell-crank levers connected to the forward end portions of said band for closing the band laterally of the shoe, rack bars connected to said bell-crank levers and movable in unison in the same direction to close the band, a power-operated member for thus moving said rack bars, means for preliminarily adjusting the rack bars relatively to said power-operated member to vary the distance between the forward ends of the band, and means for also preliminarily adjusting the rack bars respectively in opposite directions to shift the forward ends of the band simultaneously to the right or the left laterally of the shoe. 65
- 65 27. In a heel-end lasting machine, a heel band for embracing the heel end of a shoe, members 70
- 70 75

connected to the forward end portions of said band and movable laterally of the shoe to close the band, and operating means movable lengthwise of the shoe to operate said members, said 5 operating means comprising parts relatively movable lengthwise of the shoe to effect a preliminary adjustment of the forward ends of the band laterally of the shoe.

28. In a heel-end lasting machine, a heel band 10 for embracing the heel end of a shoe, members connected to the forward end portions of said band and movable laterally of the shoe to close the band, and operating means movable lengthwise of the shoe to operate said members, said 15 operating means comprising parts movable relatively to each other in opposite directions respectively to shift the forward ends of the band simultaneously to the right or the left.

29. In a heel-end lasting machine, a heel band 20 for embracing the heel end of a shoe, and means comprising two connected members movable in the same direction lengthwise of the shoe to close the band laterally of the shoe, one of said members being movable relatively to the other to 25 adjust the forward ends of the band preliminarily toward or from each other.

30. In a heel-end lasting machine, a heel band 30 for embracing the heel end of a shoe, means comprising two connected members movable in the same direction lengthwise of the shoe to close the band laterally of the shoe, one of said members being movable relatively to the other to adjust the forward ends of the band preliminarily toward or from each other, and gearing movable 35 in part with said members and in part supported independently thereof for effecting such adjustment.

31. In a heel-end lasting machine, a heel band 40 for embracing the heel end of each shoe, an abutment for engaging the rear end of said heel band to support the band against pressure of the shoe thereon, said abutment and band being relatively movable in directions lengthwise of the shoe, and spring means for pressing the band 45 against the shoe in locations substantially opposite the corners of the heel end of the shoe, said spring means being arranged to position said band and abutment relatively out of contact with each other prior to pressure of the band on the 50 shoe and being yieldable to permit relative movement of the band and abutment into contact with each other as the pressure is applied.

32. In a heel-end lasting machine, a heel band 55 for embracing the heel end of each shoe, a shoe support movable to force the shoe against said heel band, an abutment arranged to engage the rear end of the band to support the band against pressure of the shoe thereon, the band being movable in directions lengthwise of the shoe relatively to said abutment, and spring-pressed 60 plungers for pressing the band against the shoe in locations substantially opposite the corners of the heel end of the shoe, said plungers being arranged to position the band initially in spaced 65 relation to said abutment and being yieldable to permit the band to be forced against said abutment by pressure of the shoe thereon.

33. In a heel-end lasting machine, a heel band 70 for embracing the heel end of each shoe, members arranged to press the band inwardly against the shoe in locations substantially opposite the corners of the heel end of the shoe, springs for forcing said members inwardly toward the band, 75 and supports for said members and springs ad-

justable in directions toward or from the band without altering the stresses of the springs.

34. In a heel-end lasting machine, a heel band 5 for embracing the heel end of each shoe, plungers arranged to press the band inwardly against the shoe in locations substantially opposite the corners of the heel end of the shoe, bushings supporting said plungers, springs in said bushings for forcing the plungers inwardly toward the band, and members adjustable in said bushings 10 to vary the stresses of the springs, the bushings being adjustable with the plungers and springs in directions toward or from the band.

35. In a lasting machine, the combination with 15 a shoe support, and end-lasting wipers for wiping an end of the upper of a shoe on said support into lasted position, of a plurality of drivers for driving fastenings to fasten the upper, and means for operating said drivers with less force 20 when there is no shoe on the shoe support than when a shoe is mounted on said support.

36. In a lasting machine, the combination with 25 a shoe support, and end-lasting wipers for wiping an end of the upper of a shoe on said support into lasted position, of a plurality of drivers for driving fastenings to fasten the upper, a member 30 movable to operate said drivers, means for operating said member, and shoe-controlled means for rendering said operating means effective to operate said member with greater force when there is a shoe on said support than when no shoe is mounted thereon.

37. In a lasting machine, the combination with 35 a shoe support, and end-lasting wipers for wiping an end of the upper of a shoe on said support into lasted position, of a plurality of drivers for driving fastenings to fasten the upper, spring means for operating said drivers either with a shoe on said support or in the absence of such a shoe, and additional spring means for increasing 40 the force with which the drivers are operated only when a shoe is mounted on the shoe support.

38. In a lasting machine, the combination with 45 a shoe support, and end-lasting wipers for wiping an end of the upper of a shoe on said support into lasted position, of a plurality of drivers for driving fastenings to fasten the upper, a member 50 movable to operate said drivers, spring means for operating said member either with a shoe on said support or in the absence of such a shoe, additional spring means for also operating said member, and mechanism arranged to be controlled by a shoe on said support for rendering said additional spring means operative only when a shoe is mounted on the support. 55

39. In a lasting machine, the combination with a shoe support, and end-lasting wipers for wiping an end of the upper of a shoe on said support into lasted position, of a plurality of drivers for driving fastenings to fasten the upper, a member 60 movable to operate said drivers, spring means for operating said member, a holdown movable by contact of a shoe therewith, and mechanism controlled by said holdown for rendering said spring means effective to operate said member 65 with greater force when there is a shoe on said support than when no shoe is mounted thereon.

40. In a lasting machine, the combination with a shoe support, and end-lasting wipers for wiping an end of the upper of a shoe on said support 70 into lasted position, of a plurality of drivers for driving fastenings to fasten the upper, a member movable to operate said drivers, spring means for operating said member either with a shoe on said support or in the absence of such a shoe, ad- 75

ditional spring means for also operating said member, a device for locking said additional spring means normally out of action, and means arranged to be controlled by a shoe on said support for operating said device to unlock said additional spring means only when a shoe is on said support.

41. In a lasting machine, the combination with a shoe support, and end-lasting wipers for wiping an end of the upper of a shoe on said support into lasted position, of a plurality of drivers for driving fastenings to fasten the upper, a member movable to operate said drivers, spring means for operating said member, additional spring means for also operating said member, said additional spring means comprising a bar and a spring for operating the member through said bar, a device for locking the bar against movement or for releasing it to permit its movement by the spring, and a lost-motion connection between said bar and the driver-operating member to permit the movement of said member by the first-mentioned spring means when the bar is locked.

42. In a lasting machine, the combination with a shoe support, and end-lasting wipers for wiping an end of the upper of a shoe on said support into lasted position, of a plurality of drivers for driving fastenings to fasten the upper, a member movable to operate said drivers, stop mechanism for limiting movement of said member by impact, a comparatively light spring for operating said member, a heavier spring for also operating said member, and means for rendering said heavier spring either operative or inoperative when said light spring is operating the member.

43. In a lasting machine, the combination with a shoe support, and end-lasting wipers for wiping an end of the upper of a shoe on said support into lasted position, of a plurality of drivers for driving fastenings to fasten the upper, a member movable to operate said drivers, a plurality of springs for operating said member, and controlling means for either rendering all the springs or less than the total number thereof operative on said member.

44. In a lasting machine, the combination with a shoe support, and end-lasting wipers for wiping an end of the upper of a shoe on said support into lasted position, of a plurality of drivers for driving fastenings to fasten the upper, a spring-impelled member movable to operate said drivers, a stop carried by said member, means for engaging said stop to limit the movement of the member, and means carried by said member for adjusting the stop to vary the limit of movement of the member.

45. In a lasting machine, the combination with a shoe support, and end-lasting wipers for wiping an end of the upper of a shoe on said support into lasted position, of a plurality of drivers for driving fastenings to fasten the upper, a spring-impelled member movable to operate said drivers, a stop carried by said member, means for engaging said stop to limit the movement of the member, and an eccentric supporting said stop and rotatable to adjust the stop for varying the limit of movement of the member.

46. In a lasting machine, the combination with a shoe support, and end-lasting wipers for wiping an end of the upper of a shoe on said support into lasted position, of a plurality of drivers for driving fastenings to fasten the upper, a member movable to operate said drivers, and means car-

ried by said member for adjustably limiting the movements of the drivers to cause them to drive fastenings either fully into a shoe or only part way into a shoe.

47. In a lasting machine, the combination with a shoe support, and end-lasting wipers for wiping an end of the upper of a shoe on said support into lasted position, of a plurality of drivers for driving fastenings to fasten the upper, means for variably limiting the movements of said drivers to cause them to drive fastenings either fully into a shoe or only part way into a shoe, and means for operating the drivers with greater force in fully driving the fastenings than in driving them only part way into a shoe.

48. In a lasting machine, the combination with a shoe support, and end-lasting wipers for wiping an end of the upper of a shoe on said support into lasted position, of a plurality of drivers for driving fastenings to fasten the upper, a member movable to operate said drivers, means for variably limiting the movement of said member to cause the drivers to drive fastenings either fully into a shoe or only part way into a shoe, spring means for operating said member, and additional spring means for increasing the force with which said member is operated only when the fastenings are fully driven.

49. In a lasting machine, the combination with a shoe support, and end-lasting wipers for wiping an end of the upper of a shoe on said support into lasted position, of a plurality of drivers for driving fastenings to fasten the upper, a member movable to operate said drivers, means for variably limiting the movement of said member to cause the drivers to drive fastenings either fully into a shoe or only part way into a shoe, a plurality of springs for operating said member in driving fastenings fully into a shoe, and means for maintaining a portion only of the total number of springs inoperative in driving fastenings only part way into a shoe.

50. In a lasting machine, the combination with a shoe support, and end-lasting wipers for wiping an end of the upper of a shoe on said support into lasted position, of a plurality of drivers for driving fastenings to fasten the upper, a member movable to operate said drivers, spring means for operating said member either with a shoe on said support or in the absence of such a shoe, additional spring means for also operating said member, mechanism arranged to be controlled by a shoe on said support for rendering said additional spring means operative only when a shoe is mounted on the support, and means movable at the will of the operator for preventing the operation of said additional spring means even though a shoe is on the support.

51. In a lasting machine, the combination with a shoe support, and end-lasting wipers for wiping an end of the upper of a shoe on said support into lasted position, of a plurality of drivers for driving fastenings to fasten the upper, a member movable to operate said drivers, spring means for operating said member either with a shoe on said support or in the absence of such a shoe, additional spring means for also operating said member, a device for locking said additional spring means normally out of action, mechanism arranged to be controlled by a shoe on said support to cause said device to unlock said additional spring means, and means whereby said device may be maintained in locking position regardless of the action of said mechanism.

52. In a lasting machine, the combination with

75

- a shoe support, and end-lasting wipers for wiping an end of the upper of a shoe on said support into lasted position, of a plurality of drivers for driving fastenings through openings in the wipers
- 5 to fasten the upper, means for limiting the movements of the drivers to cause them to drive the fastenings only part way into a shoe, and mechanism for effecting relative movement of the shoe and the wipers heightwise of the shoe after the
- 10 driving of the fastenings to clear the fastenings from the openings in the wipers.
53. In a lasting machine, the combination with a shoe support, and end-lasting wipers for wiping an end of the upper of a shoe on said support into lasted position, of a plurality of drivers for driving fastenings through openings in the wipers to fasten the upper, means for limiting the movements of the drivers to cause them to drive the fastenings only part way into a shoe, a hold-
- 15 down for engaging the shoe, and means for operating said holdown to move the shoe heightwise far enough to clear the fastenings from the openings in the wipers after the driving of the fastenings.
- 20 54. In a heel-end lasting machine, the combination with heel-end lasting means, of a support for a long-legged boot movable to carry the boot lengthwise toward said lasting means, said support comprising a pair of members each slidably
- 25 mounted for upward and downward movements with a boot supported by the members, means on one of said members for supporting the boot at the heel end, means on the other member for supporting the boot at the forepart, and a connection between said members so located as to
- 30 be out of the way of the leg of any boot and ar-
- 35 ranged to maintain the members in fixed relation

to each other in their upward or downward movements.

55. In a heel-end lasting machine, the combination with heel-end lasting means, of a support for a long-legged boot mounted for swinging movement to carry the boot lengthwise toward the lasting means, said support comprising a pair of rods each slidably mounted for upward and downward movements, means on one of said rods for supporting a boot at the heel end, means on the other rod for supporting the boot at the forepart, an arm connecting said rods together for movements in unison and so located as to be out of the way of the leg of any boot, and means for raising both rods with the boot to

10 15 position the latter in proper relation to the lasting means.

56. In a power-operated heel-end lasting machine, the combination with heel-lasting wipers, of means for clamping a shoe to hold it for the operation of said wipers, two members so mounted as to permit them to turn either as a unit or relatively to each other about the same axis, connections between one of said members and the clamping means for operating said means, and a pin mounted in the other member and arranged to engage and operate the member thus connected to the clamping means by the turning movement of said other member, said pin having a recess in one side thereof and being rotatable

20 25 30 into a position for its recessed portion to clear the member which it operates and thus to relieve the clamping pressure on the shoe if the operation of the machine is stopped by abnormal resistance of the shoe to the movement of the 35 wipers.

JACOB C. JORGENSEN.
